L. S. RILEY.
MOUNTING CORNER.
APPLICATION FILED JULY 14, 1919.

Patented Dec. 23, 1919.

FIG. I

FIG. II

UNITED STATES PATENT OFFICE.

LESTER S. RILEY, OF GREENWOOD, MASSACHUSETTS, ASSIGNOR OF FIVE-EIGHTHS TO
SAMUEL L. SNEIDERSON, OF ROXBURY, MASSACHUSETTS.

MOUNTING-CORNER.

1,326,139.

Specification of Letters Patent. Patented Dec. 23, 1919.

Application filed July 14, 1919. Serial No. 310,851.

To all whom it may concern:

Be it known that I, LESTER S. RILEY, a citizen of the United States, residing at Greenwood, county of Middlesex, Commonwealth of Massachusetts, have invented 5 certain new and useful Improvements in Mounting-Corners, of which the following is a specification.

In the mounting of photographs, post-cards and the like, whether in albums or on other surfaces, it has been proven highly desirable to have the print held lightly and yet firmly without that finality which mounting by means of paste renders unavoidable. Corner mounting has proven to be a very satisfactory manner of effecting this result and various systems and devices have been provided for holding the print by the corner.

20 The problem of providing an artistic and effective mount in a simple and commercial form is not simple as the requirements are varied and practical difficulties attend each requirement.

25 The object of my present invention is to provide corner mounts which will fulfil a maximum number of these requirements with a minimum of difficulty and all at a low cost, making the article practically available for general use.

30 The advantages effected by my invention are briefly as follows:

By it I provide individual corner pockets upon any part of a page or mount. Their utility is therefore general as they may be attached to any surface without previous preparation of it as a mount. The devices in accordance with my invention may be produced from ready gummed stock, being 35 so devised that in folding they become self-forming and self-attaching making them complete units and permanent fixtures.

40 In accordance with my invention it is also possible to produce these units in group sets so that they may be conveniently handled and so that sets in varied colors may be had without confusion and without delay incident to sorting.

45 These and various other features are 50 prominently characteristic of my invention. As illustrative of it I have shown in the accompanying drawings a form which I have found highly successful for practical use and which I will describe in detail in

the specification which follows. In the drawings:

Figure I is a view of a mounting in accordance with my invention.

Fig. II a plan view of a corner unit.

Fig. III a group set of units.

Fig. IV an indicated section on the line IV—IV, Fig. II.

Fig. V an enlarged section through corner on the line V—V, Fig. I, and

Fig. VI a general view of a corner folded.

Referring now to the corner unit herein employed as illustrative of my invention, it will be seen by reference to Fig. II that each corner unit consists of a flat paper stamping comprising a somewhat V-shaped exposed 70 section 1. The shape is generally that of a right triangle being notched or cut out at 2.

On the equilateral sides of the piece 1 I form two flaps, one a preferably square flap indicated at 3 and the other a triangular flap indicated at 4. The triangular flap is preferably similar to the section 1 except that it is not notched or cut out. The flap 3 is preferably twice the area of the flap 4, the flap 4 being really the triangular half 80 of the area 3 divided on its diagonal.

The flap 3 is also scored lightly at *d*, *e* leaving an area 3¹ which may be folded back as indicated in Fig. VI to bring a small area of gummed surface next to the back of 85 the mount or photograph P where it is desired to give some permanence of attachment between the corner and the print. This is sometimes desirable where the corners are folded on the print first or where 90 it is not intended to remove the print. It may be here noted that while the flap 3¹ affords considerable permanency of attachment so that the print or photograph is not easily dislodged from the corner, it is still 95 possible without destroying the photograph to peel it loose from the corner 3¹ by drawing back the corner of the print which thus rolling strips off the gummed corner 3¹ with the practical certainty that the print 100 will not be destroyed or injured.

The corner blank as shown in Fig. II is struck from glued stock and may be considered as lying in Fig. II gummed side up. The upper surface of the flaps 3 and 105 4 are therefore gummed surfaces. The surface of the corner or exposed portion 1 was originally a gummed surface but in striking

out these blanks I preferably print the surface 1 in some color. This adds to the artistic effect of the corner making it possible to use a mount harmonizing or artistically contrasting in color with the back ground or with the tone of the print. The printing of the surface 1 also destroys the adhesive nature of its gumming so that the surface is no longer sticky and will not attach to an opposite page in case an album is used.

10 The corner 1 in addition to the printing is also preferably embossed making the exposed portion highly attractive and adding to it considerable rigidity and decreasing 15 possibility of tearing when the corner of the print is inserted.

15 Each corner unit is preferably scored along the lines $a-b$, $b-e$, and the section 3¹ is also scored along the line $d-e$. This 20 permits the corners to be folded with rapidity and certainty.

25 In folding the flap 3 is preferably folded first and the flap 4 turned over it as indicated in Fig. VI. Where it is desired to simply stick the corner on the mount and then insert the print afterward it is only necessary to make one moistening of the flaps thus folded inasmuch as the surface of the flap 4 only covers half of the surface 30 of the flap 3.

35 Where it is desired to attach the corner to the print the contacting surfaces of the flap 4 and the flap 3 may be permanently united giving the corner the permanent form which may be utilized afterward as desired.

40 As heretofore pointed out articles of this sort are used in sets usually of four. Where different colors, designs and effects are used it is important that these sets be kept together to avoid the necessity of sorting and to give convenience in handling.

45 In accordance with my invention I am able to produce my corner in set groups as indicated in Fig. III. It will be noted that this set group is a rectangular group from which only four small notches are struck out as waste. A group may therefore be produced from a continuous strip of the proper width. 50 In order that the corner units may be readily detachable and yet that the group as a whole may remain together I partially sever the set blank into its corner units along the lines of demarcation of the unit blanks 55 which I have indicated in Fig. III, by dotted line, as distinguished from the dotted and dash line which indicates the line of fold at $a-b$, $b-e$, $d-e$. This line of semi-detachment may readily be traced in Fig. 60 III, being practically four right angular arms radiating from the center in the form of the well known swastika symbol.

65 While I do not limit myself to the particular form of corner shown or to the particular set group, it will be appreciated that

both the form and the group arrangement are highly advantageous both as a matter of practical press production and of commercial handling where these articles have to be accurately counted and enveloped for distribution. The fact that the set group is gummed only on one side is of great importance in manufacture and also of great importance in handling, inasmuch as the groups may be stacked with the adhesive 70 side of one against the non-adhesive side of the other.

75 While I have shown and particularly described in this application this highly developed form with its various advantages 80 above explained, I am not to be understood as limiting myself to any one of the specific features or combinations of features thus described except as hereinafter defined by my claims.

85 What I therefore claim and desire to secure by Letters Patent is:

1. An article of the class described comprising a corner piece, a rectangular flap and a triangular flap foldably attached to the margins thereof, said flaps having 90 gummed backs.

2. An article of the class described comprising a corner piece of substantially triangular shape, a rectangular flap and a triangular flap foldably attached to the margins thereof, said flaps having 95 gummed backs.

3. An article of the class described comprising a substantially V-shaped corner 100 piece, a rectangular flap and a triangular flap foldably attached to the margins thereof, said flaps having gummed backs.

4. An article of the class described comprising a flat blank gummed on the back 105 and including an exposed part and foldable flap parts, the gummed surface of the exposed part being printed whereby the exposed surface is rendered non-adhesive.

5. An article of the class described comprising a flat blank gummed on the back 110 and including an exposed part and foldable flap parts, the gummed surface of the exposed part being treated to render it non-adhesive.

6. An article of the class described comprising a flat blank gummed on the back and including a substantially triangular front part, and foldable flaps, the gummed surface of the front part being rendered 120 non-adhesive by printing.

7. An article of manufacture consisting of a blank containing a set of detachable units, each comprising a front area and a pair of flap areas, said units being partially 125 severed from each other in the blank group.

8. An article of manufacture consisting of a blank containing a set of four detachable units, each comprising a foldable corner mount, each of one-fourth the area of the 130

blank, said units being partially severed from each other in the blank group.

9. An article of manufacture consisting of a substantially rectangular blank containing a set of units, each comprising a rectangular area and a pair of triangular areas each of one-half the area of the square, said units being partially severed from each other in the blank group.
10. A mount of the class described, comprising a corner receiving pocket, and a foldable portion having a gummed surface adapted to be disposed outwardly for attachment to the article to be mounted.
- 15 11. As a new article of manufacture and

sale, a gummed sheet scored along predetermined lines of severance to produce a plurality of similar corner receiving pockets for mounting a photograph or the like.

12. A series of detachable mounts for a photograph or the like, formed from a sheet of material gummed on one face, said mounts being partly severed each from the other in said sheet.

In testimony whereof I affix my signature 25
in presence of two witnesses.

LESTER S. RILEY.
